D. Anthony Kima ATTORNEY

UNITED STATES PATENT OFFICE.

WILLIAM G. WILLIAMS, OF FLUSHING, NEW YORK, ASSIGNOR TO WADDELL & HARDESTY, OF NEW YORK, N. Y., A COPARTNERSHIP COMPRISING JOHN A. L. WADDELL AND SHORTRIDGE HARDESTY.

ATTACHMENT FOR CABLES OF LIFT BRIDGES.

Application filed February 17, 1927. Serial No. 168,969.

My invention aims to provide certain improvements in the direction of simplicity and efficiency in connecting lifting ropes to the lift spans of bridges and to similar apparatus.

The accompanying drawings illustrate embodiments of the invention.

Fig. 1 is a side elevation of a lift bridge, omitting the parts which have no relation to the present invention;

Fig. 2 is a face elevation of one end of one of the lift girders which extend across the ends of the lift span;

Fig. 3 is a cross-section of Fig. 2 on the line 3—3;

Fig. 4 is a horizontal section on the line 4—4 of Fig. 2;

Fig. 5 is a horizontal section on the line 5—5 of Fig. 2.

The figures illustrate the improved method of attachment of the ropes which support the counterweights to one end of one of the lifting girders of the span. There are sixteen ropes shown. These will be repeated at the opposite side of the same girder, and a similar arrangement of thirty-two ropes will be provided for the girder at the opposite end of the span; each setting of sixteen ropes carrying one of the counterweights. The invention, however, may be adapted to groups of a larger or smaller number of ropes as required by the circumstances of the structure.

Referring to Figs. 2 and 3, special rope sockets 1 are shown adapted to the ends of the several ropes 2. Each socket has a head 3 at its lower end to aid in gripping the sockets when assembling or adjusting the ropes. The ropes are attached in the sockets in any ordinary way. At the upper ends of the sockets are located shims 4 for adjustment of the lengths of the ropes; the shims being circular and threaded on the ropes before attachment of the sockets, in which case excess shims might afterwards be wired to the ropes, or they may be made in the form of slotted or U-shaped washers which can be inserted or withdrawn more easily. Keys 5, Fig. 3, may be added at top and bottom of the shims to maintain them in correct position.

In Fig. 3 the upper parts of the ropes 2 are shown in full lines in the angular posi-

tions which they assume when the span is at the high point of its lift. When the span is lowered, the convergence of the ropes 2 in the upward direction becomes less and they are nearly parallel in the lowest position of the span, their angularity for this position being indicated in dotted lines. The guide 60 sheave or pulley 6 over which they run is supported at the top of the towers 7, Fig. 1, between which the span 8 rises and falls. The ropes which are to pass to opposite sides of the lift girder 9 are spread into two groups of eight each by a spreader 10 which is supported on the top flange or plate 11 of the girder. Of the eight ropes on each side, a group of four alternately spaced terminates at about the centre of the depth of the girder, and the other group of four extends to a point below the bottom flanges or plate 12 of the girder. By this means the eight ropes are brought so close together as to leave only sufficient space between them 70 as they lead up to the sheave, for the eight ropes leading up from the opposite side of the girder.

The upper ends of the sockets of the shorter ropes bear against the undersides of plates 13 supported on the undersides of angles 14 which are riveted to the web of the girder and which in turn are braced in the vertical direction by stiffeners 15 in the form of angles (Fig. 5) also riveted to the web 85 of the girder. The bearing plates 13 at the opposite sides of the girder may be made in one piece and passed through a slot in the web 9 of the girder; but the arrangement shown in Fig. 3 is preferable in which a separate plate 13 is used on either side of the web and the opposite plates are united by bolts 16 extending through from side to side and calculated to distribute the loads evenly on the angles and stiffeners at the two sides 90 of the web.

The longer ropes have sockets 1 with heads 3 and carry shims 4 and keys 5 similar to those of the shorter ropes. The shims bear on the lower flange 12 of the girder, 100 preferably through the intermediation of a reinforced gusset 17 (Fig. 4) attached to the underside of the flange. The flange 12 in turn bears through angles 18 against vertical stiffeners 19 which transfer the load 105 to the web of the girder.

To allow the assembly of the ropes as illustrated the flanges 11 and 12 at the top and bottom of the girder, the angles 13 and 18, the gussets 17 and the spreader block 10 are provided with slots which permit the ropes to be entered from the sides of the lifting girder and pushed into place as close as possible to the web. The slots in the gussets, however, do not have to extend to the outer edges but are extended only sufficiently to form holes 20 which are of sufficient size to permit the passage of the rope sockets 1 as indicated in dotted lines in Fig. 4. The ropes are held in their respective slots by keepers or bars 21, Figs. 2 and 3, bolted to the spreader block 10. Similar keepers may be provided over the rope sockets or the ropes at other points if desired.

With the method of connection described, we may practically eliminate any transverse leads from the ropes to the bridge structure as they lead downward from the sheaves, the maximum distance for any one rope from the centre of the lifting girder being about one-half the center to center distance of the rope grooves on the sheave 6. The ropes can be quickly and efficiently adjusted or replaced. The height to which the span can be raised is not restricted except by the clearance requirements of the structure; that is, it is not limited by any transverse lead of the ropes.

Many modifications and re-arrangements of the parts shown may be made. The connections described may be adopted for ropes which lead to the counterweights, as shown or for ropes which serve to lift the span in other ways, and the improvements may be applied wherever it is desired to connect lifting ropes to similar structures.

Various other modifications may be made by those skilled in the art without departing from the invention as defined in the following claims.

What I claim is:

1. A lift bridge including in combination a girder extending transversely of the span and lifting ropes leading upward therefrom

and located respectively on opposite sides of the girder.

2. A lift bridge including in combination a lift girder, a plurality of ropes operatively engaging the same, and a spreader on top of the girder for directing said ropes respectively to either side of the girder, the ropes converging upward above the spreader and being substantially parallel below it.

3. A lift bridge including in combination a lift girder, a plurality of lifting ropes operatively engaging the same, a first group of said ropes engaging the girder at one level and a second group located between and parallel and close to those of the first group and engaging the girder at a lower level.

4. A lift bridge including in combination a lift girder, a plurality of lifting ropes operatively engaging the same, a first group of said ropes engaging the girder at about the middle of its height and a second group located between and parallel and close to those of the first group and engaging the girder at about its lower edge.

5. A lift bridge including in combination a lift girder, extending transversely of the span and lifting ropes on opposite sides of the girder, the ropes on each side being in two groups of alternate ropes engaging the girder at different levels.

6. A lift bridge including in combination a lift girder, plates fastened to the opposite sides of the girder, a plurality of ropes in two groups at opposite sides of the girder and engaging said plates, the plates at one side of the girder being united to those at the other side to balance the strains at the two sides.

7. A lift bridge including in combination a lift girder, a plurality of ropes operatively engaging the same, and a gusset extending horizontally across the bottom of the girder and engaged by said ropes.

In witness whereof, I have hereunto signed my name.

WILLIAM G. WILLIAMS.
